(Cl. D64—11)

FIG.1

FIG.2

FIG. 3

FIG. 4

FIG. 5

FIG. 1 is a perspective front view;

FIG. 2 is a view seen partly from the front and partly from the side;

FIG. 3 is a side view;

FIG. 4 is a top view; and

FIG. 5 is a rear view of our design.

The essential features of the design reside in the portions shown in solid lines.

We claim:

The ornamental design for a typewriter or the like, substantially as shown and described.
